UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK

TESTING ARRANGEMENT FOR TELEPHONE-EXCHANGE SYSTEMS.

1,246,548.

Specification of Letters Patent Patented Nov. 13, 1917.

Application filed November 1, 1916. Serial No. 128,868.

To all whom it may concern:

Be it known that I, HENRY P. CLAUSEN, a citizen of the United States, residing at Mount Vernon, in the county of Westchester and State of New York, have invented certain new and useful Improvements in Testing Arrangements for Telephone-Exchange Systems, of which the following is a full, clear, concise, and exact description.

10 This invention relates to an arrangement for automatically performing routine tests in telephone-exchange systems. The particular test which the arrangement of the invention is adapted to perform is a test of the general operation of an automatic switch or switches in extending a connection between two subscribers' lines.

In accordance with the invention automatic means are provided which are adapted 20 to be associated with the switch or switches under test, and when so associated are adapted to control such switch or switches in their standard operation in establishing a test connection. If the connection thus controlled is established within a predetermined time, it is assumed that the switches are operating in a standard manner. If, on the other hand, the connection is not established within such predetermined time, the operation 30 of the switch is considered as being unstandard and a record is made of such fact, such record being also made automatically.

In automatic telephone exchange systems 35 it is a requirement that the automatic switches used in establishing a connection should respond to impulses of a certain definite speed, and heretofore that they should complete their operation within a definite time. A switch is considered to be operating under standard conditions if it will respond to impulses varying from 8 to 12 impulses per second, 10 impulses being considered the standard, and two impulses per second, more or less, being considered as an allowable variation. Therefore, it becomes necessary, in order to determine whether the switches are in standard condition, to operate such switches by means of impulses 45 which occur within the allowable limits of 8 to 12 per second, and to determine whether or not the switches will operate in response to such impulses.

In accordance with a feature of the invention 50 a plurality of switches to be tested are

adapted to be successively associated with a testing arrangement, which testing arrangement is adapted to make the following tests: first, to determine whether the particular switch under test is idle; second, to determine whether such switch will operate to extend a particular test connection in response to 10 pulses per second, then in response to 8 pulses per second and finally in response to 12 pulses per second. If the switch is found to be busy, the testing arrangement is immediately associated with another switch to be tested. If the switch fails to operate in the standard manner in response to the various pulses, a record is automatically made of such fact and the testing arrangement is then associated with the next switch to be tested.

The invention may be more clearly understood from a consideration of the accompanying drawings, in which Figure 1 represents diagrammatically a connector switch and a testing arrangement for testing a plurality of such switches. Figs. 2 and 3 together show a line switch, selector switch and connector switch and a testing arrangement for testing a plurality of such switches.

The invention will first be described in connection with a test of connector switches.

Referring to Fig. 1, that part of the figure above the broken line shows diagrammatically an ordinary connector switch of the type in which a brush carriage is first stepped vertically in response to controlling impulses and then is rotated also in response to controlling impulses to the terminal of the desired line, such type of switch being well-known in the art. The circuits of the switch will not be described in detail, as their operation will be clear from the description of the operation of making the test. Below the broken line in Fig. 1 is shown the testing arrangement, which comprises an automatic switch of known construction, adapted to associate the testing devices with a plurality of connector switches. This automatic switch is provided with a plurality of brushes 1, 2 and 3, which are adapted to make contact with rows of contacts, 4, 5 and 6; 7, 8 and 9. Each set of three contacts of this automatic switch is connected to the trunk conductors 10, 11 and 12 of a plurality of connector switches, only one of which is shown.

in Fig. 1. The brushes 1, 2 and 3 are adapted to be stepped over the rows of contacts 4, 5 and 6, and 7, 8 and 9, in response to the intermittent energization of the stepping magnet 13. The brushes of the automatic switch are adapted to be connected to a plurality of sending devices indicated at 14, 15 and 16. These impulse sending devices may be of any well-known character such as the ordinary finger wheel, and may be, and preferably are, automatically operated. In the arrangement indicated, three cams are provided with suitable teeth, which cams are adapted to be power driven at different speeds, cam No. 14 being driven at a speed to produce pulses at the rate of 10 per second, cam 15 being adapted to produce pulses at the rate of 8 per second, and cam 16 to produce pulses at the rate of 12 per second.

20 In order to connect the impulse senders in succession in operative relation to the switch under test, a step-by-step sequence or side switch is provided, the magnet of which is indicated at 17. The arrangement is such that each time the magnet 17 is energized, a cam shaft controlled thereby, is moved through a single step or position, which in each position, opens or closes certain contact springs which are indicated on the drawing, the number of the position in which such contact springs are opened or closed being indicated by the number adjacent to such contact springs. A set of contacts of the connector switch to be tested, which are indicated at 18, 19 and 20, are connected in multiple with similar contacts of other switches to conductors leading to the testing arrangement. One of these conductors includes a relay indicated at 21 which corresponds to the ordinary cut-off relay of a line, and the other two conductors are connected to suitable apparatus associated with the testing arrangement which will be described more in detail in describing the operation of such testing arrangement.

In general, in performing a test, the testing arrangement is brought into association with the connector switch by means of the automatic switch whose stepping magnet is indicated at 13. The testing arrangement thereupon operates to determine if the connector is busy or idle. If the connector is idle, it is seized and through the instrumentality of one of the impulse senders, a series of impulses is sent to the connector switch to cause it to move its brushes into contact with the set of terminals leading back to the testing arrangement. If this connection is established within a predetermined time, the testing arrangement will operate to set up another connection at a different rate of speed.

The operation of the testing arrangement, assuming first that the connector is busy, 65 will now be described.

It will be assumed that the set of brushes 1, 2 and 3 has been brought into contact with the contacts 4, 5 and 6, and that the manual switch indicated at 22 has been closed. If the switch shown at Fig. 1 is busy, the relay 23 will have been operated and the ground will be thereby placed upon the contact 6. Under these conditions a circuit will be established from battery 24, through the lower arm of the manual switch 22, through sequence switch contact 25 in position 1, back contact and outer left-hand armature of relay 28, relay 14, back contact and left-hand armature of relay 26, to ground. Relay 14 will thereupon be energized, and in attracting its armatures will connect the brushes 1, 2 and 3 to the sequence switch springs 27 and 29. As soon as relay 14 is operated a circuit is established for the relay 26 from battery 24, lower armature of the manual switch 22, sequence switch 25 in position 1, relay 26, sequence switch spring 27 in position 1, armature and front contact of relay 14, brush 3, contact 6 to ground at the left armature and contact of relay 23. Relay 26 thereupon operates and opens the circuit previously traced for the relay 14, at the same time closing a locking circuit for itself through its front contact and left-hand armature. Relay 14 in deenergizing, disconnects the testing arrangement from the brushes 1, 2 and 3, so that there is no further interference with the connector switch. Relay 26 in operating, also closes a circuit for the sequence switch 17 from battery 30, sequence switch magnet 17, front contact and right armature of relay 28, interrupter 31, upper arm of the manual switch, to ground. As the interrupter 31 rotates, impulses will be sent to the sequence switch 17, which will step such sequence switch from position to position until when position 13 is reached, a circuit is closed for the stepping magnet 13 of the automatic switch which may be traced from battery 24 to the lower arm of the manual switch 22, sequence switch spring 25 in position 13, stepping magnet 13 to ground. In response to the energization of the stepping magnet 13, the brushes of the switch are advanced to another row of contacts.

Under control of interrupter 31 and sequence switch contact 32, magnet 17 is energized and the sequence switch contacts are moved into their first positions where the test is repeated for another connector switch.

It will now be assumed that the switch shown in Fig. 1 is idle. Therefore, as soon as the brushes 1, 2 and 3 are brought into contact with the row of terminals 4, 5 and 6, the manual switch 22 being closed, a circuit will be established as before for the magnet 14, which magnet in operating will connect the brushes to the sequence switch contacts 27 and 29. In position 1 of the sequence

switch, the relay 26 is connected through the spring 27 to the brush 3 and through the contact 6 to the conductor 12. As the switch is idle, however, at this time there is no ground on the connector 12, and the relay 26 does not operate. The sequence switch is stepped out of position 1 when the power magnet thereof is energized over a circuit from battery 30, through the power magnet 17, sequence switch contact 32 in position 1, interrupter 31, upper arm of the manual switch 22, to ground. When the sequence switch is thus stepped into position 2, the contacts 27 and 29 in connection with the contacts 33 and 34 also in position 2, connect the impulse sender 14 across the brushes of 1 and 2. As the impulse springs 35 and 36 are closed in the normal position of the impulse sender 14, the effect on the connector 15 switch will be identical with that which takes place when such connector switch is seized either by a calling line or another switch; that is, a circuit will be established for the line relay 37 at such connector switch 20 from battery, through the upper winding of the relay 37, back contact and upper armature of relay 38, conductor 10, contact 4, brush 1, armature and contact of relay 14, sequence switch 29 in position 2, sequence switch 33 in position 2, contacts 35 and 36, sequence switch spring 34 in position 2, sequence switch spring 27 in position 2, armature and contact of relay 14, brush 2, contact 5, conductor 11, inner lower armature of relay 38 and back contact thereof to lower winding of relay 37 and ground. Relay 37, when energized, closes a circuit for the slow release relay 23 which may be traced from battery, through relay 23, armature and front contact of relay 37 to ground. The operation of relay 23 places ground upon conductor 12 and renders the particular connector switch under test busy, and guards such connector switch against seizure by a selector or calling line. It will be assumed that the impulser 14 has been started by suitable mechanism, not shown, and as soon as the teeth cut upon the periphery of the impulse wheel 14 are engaged by the spring 46, the circuit of the line relay 37 will be interrupted the number of times represented by the teeth. It will be noted that each of the impulse wheels is provided with first five teeth and then three teeth, so that during the rotation of the wheel 14, the circuit of the line relay will be interrupted five times followed by a long make of the circuit and then will be interrupted three times. It will be assumed also that the set of terminals 18, 19 and 20 are the third set in the fifth row of the connector switches under test. Upon the first deenergization of line relay 38, the slow release relay 23 having been operated, the second slow release relay 39 will be operated over a circuit including the vertical magnet 40 of the connector switch, which circuit may be traced from battery through the side-switch arm 41 in position 1, vertical magnet 40, relay 39, right-hand armature and front contact of relay 23, armature and back contact of line relay 37, to ground. The operation of the slow-release relay 39 closes a circuit of the private magnet 60. In response to the intermittent energization and deenergization of the line relay 37, the vertical magnet 40 will correspondingly be energized and deenergized, and will step, in the case assumed, the wipers of the connector switch up to the fifth level of the contact bank. In response to the long closure of this circuit at the end of the first series of impulses, the relay 39 will release, thus opening the circuit of private magnet 60, which in releasing, steps the side switch controlled thereby into position 2.

The next series of impulses also intermittently energize and deenergize the line relay 37, and in response to the first deenergization of such line relay 37, the slow-acting relay 39 is again energized, this time in series with the rotary magnet 42, which energizing circuit may be traced from battery, through side-switch arm 41 in position 2, rotary magnet 42, outer and left-hand armature and back contact of the relay 43, slow-release relay 39, right-hand armature and front contact of relay 23, back contact and armature of line relay 37, to ground. In response to this series of impulses, which in the case assumed are three in number, the rotary magnet will be energized three times and hence will step the brushes of the switch in the third contact in the fifth row. In response to the energization of the relay 39, private magnet 60 was again energized in the circuit previously traced. As soon as the last series of impulses has ceased, relay 39 will release, and in turn the private magnet 60 will release and move the side switch into position 3. In an ordinary connection, if the line seized by the connector switch proves to be busy, then the test relay 43 will be energized in series with the private magnet 60 through a side-switch arm 44 in position 2, through the test relay, test brush of the connector switch, to ground on the busy line, thus holding private magnet 60 in an energized condition and preventing the movement of the side-switch arms 120 into the third position. In the case assumed, however, as the contacts upon which the connector brushes rest are connected to the testing arrangement, no such busy condition will be found, so that the relay 43 will not be energized and the side switch will be moved into position 3.

When the side switch reaches this position, the relay 21 of the testing arrangement will be energized over a circuit which may

be traced from battery through the relay 21, contact 20, test brush of the connector switch, side-switch arm 44 in position 3, to ground. A circuit will also be closed for the ringing relay indicated at 46 from battery, through the side-switch arm 41 in position 3, back contact and right-hand armature of the cut-off relay 46, relay 45, through the interrupter to ground. The intermittent operation of the relay 45, due to the interrupter, intermittently connects to the conductors leading to the testing arrangement ringing current from a generator connected to the leads 46 and 47. The path of the ringing current may be traced from the generator, through the conductor 46, the lower armature and front contact of relay 45, brush and contact 19, armature and front contact of relay 21, through the resistance 61, sequence switch contact 62 in position 2, through the condenser 48, relay 28, lower armature and front contact of relay 14, back to the contact 18 and to the brush of the connector switch, and upper armature and front contact of relay 45 to the conductor 47, and thence to the ringing generator. In this circuit the resistance 61 is proportioned to represent the usual line resistance, and the condenser 49, placed in parallel with the condenser 48 and relay 28, is proportioned to represent the usual line capacity, so that the ringing may take place under conditions which are met in signaling ordinary lines. The relay 28 will be energized over this circuit. The energization of relay 28 opens the circuit previously traced for the relay 14, which in releasing, opens the ringing circuit previously traced through relay 28.

40 The relay 28 when operated, short circuits the condenser 48 at its right-hand armature, thereby providing an energizing circuit for the relay 38, from battery, upper winding of relay 38, left armature and back contact of the private magnet 60, upper armature and back contact of relay 45, (when such relay 45 is deenergized, due to the action of the interrupter), brush of the connector, contact 18, armature and front contact of relay 14, relay 28, right-hand armature and contact of relay 28, contact spring 62, position 2, resistance 61, contact 19, brush of connector, lower armature and front contact of relay 45, lower winding of relay 38, to ground.

45 Although this circuit for relay 38 is established at the same time that the circuit for relay 14 is broken, the relay 38 operates before the relay 14 is deenergized, and as soon as the relay 14 releases the relay 38 is released. The relay 38 is therefore only momentarily energized, but is energized long enough to cause the energization of relay 46, over a circuit which may be traced from battery, through relay 46, lower arm-

ture and contact of relay 38, side-switch arm 44 in position 3 to ground. The relay 46 when energized, closes at its left armature a substitute locking circuit for itself independent of the relay 38. The relay 46 when deenergized, also opens the circuit of relay 45, and disconnects the ringing current.

50 The release of the relay 14 opens the circuit of the line relay 37, which in releasing, permits the slow release relay 23 to release. The release of this relay closes the circuit of the release magnet 63 from battery, release magnet 63, contacts of the off-normal switch 50, back contact and right armature of relay 23, lower contact and armature of relay 38 to ground, thus restoring the connection to normal.

55 The relay 28 when energized, also closes at its inner left-hand armature a circuit for the power magnet 17 of the sequence switch 85 from battery, to the power magnet 17, contact spring 32 in position 2, inner left-hand armature and contact of relay 28 to ground. The energization of the power magnet 17 moves the sequence switch from position 2 to 3. In position 3, the original energizing circuit of relay 14 is again established, and the testing arrangement is again connected thereby to the brushes 1, 2 and 3. If, in the meantime, the connector is not completely restored or has been seized by another call, the relay 26 will be energized as previously described. However, it will be assumed that the connector switch is still idle, in which case the relay 14 will remain energized and the sequence switch 17 will be moved into position 4, under the influence of interrupter 81, through contact spring 32 in position 8.

60 It will be observed that in position 4 of 105 the sequence switch, the impulse wheel indicated at 15 is connected in operative relation with the connector switch, and in response to the operation of such impulse wheel, the connector switch will be operated 110 identically as before described to extend the connection to the set of contacts indicated at 18, 19 and 20.

65 Testing and ringing will take place as before described and the relay 28 will again 115 be energized, and among other things, will release the connector as previously described. This action, of course, will take place only in case the connector switch operates in a standard manner in response to 120 the operation of the impulse wheel 15.

70 As soon as the relay 28 is energized a circuit is established for the sequence switch 17 through contact spring 32 in position 4, to drive it into position 5, in which position 125 the relays 14 and 26 are again connected in operative relation with the sequence switch in order to again determine whether the connector is idle, in the manner previously described. The sequence switch is moved 130

into position 6 under the control of the interrupter 31 by way of the contact spring 32 in position 5.

In position 6 of the sequence switch, the 5 third impulse wheel 16 is connected into operative relation with the connector switch, and a test connection is again established under the control of such impulse wheel.

10 It will be observed from the operation thus far described that in position 2 a connection will be established under the control of the impulse wheel 14, which operates at approximately ten impulses per second, and 15 in position 4 under the control of the impulse wheel 15, which operates at eight impulses per second, and in position 6 under the control of the impulse wheel 16, which operates at twelve impulses per second. 20 Similar test connections will be established under the control of the impulse senders 14, 15 and 16 in positions 8, 10 and 12, respectively of the sequence switch. However, in positions 8, 10 and 12, owing to the fact 25 that the contact spring 29 is closed at its left-hand contacts in these positions, the resistance 51, which may be in the proportion of the highest loop resistance encountered in a calling subscriber's telephone circuit, is connected in the impulse circuit, so 30 that the connections established in these positions are established under conditions such as would be present if the impulses were sent over such a line.

35 It will also be observed that the resistance 61, owing to the operation of the contact spring 62, is connected in series in the ringing circuit in positions 2, 6 and 10 of the sequence switch, and is cut out of the ringing circuit in positions 4, 8 and 12. Thus, 40 the connections which are established in positions 2, 6 and 10, are established under different conditions from those that are established in 4, 8 and 12. Thus in the 45 arrangement shown, the connector switch is automatically operated six different times under the conditions which in each case are different, and which are conditions likely to be met in establishing a normal connection 50 between a calling and a called line.

55 A recording magnet indicated at 52 is associated with the testing arrangement, and is controlled over the contact spring 53, which as indicated, is closed in positions 2, 4, 6, 8, 10 and 12 of the sequence switch. This recording magnet may be, by means 60 of any well-known device such as a dashpot, timed to operate after a predetermined time interval; and as the contact spring 53 is closed during the entire time that a connection is being established, if such a connection is established within the predetermined time, which may be three seconds, the contact spring 53 will be open before such 65 recording magnet 52 has operated, and no

record will be made of an unstandard condition. If, on the other hand, the test connection is not established in any case within the predetermined time, the recording magnet 52 will be operated and an unstandard condition will be recorded. 70

It will also be observed that the relay 28 is in all cases operated as soon as a test connection is successfully established, and that the sequence switch 17 will move from the 75 even positions to the odd positions under control of such relay, and will be moved from the odd position to the even position under the control of the interrupter 31. Thus when the last test connection is established, 80 providing it is established successfully, the sequence switch will move to position 13 under the control of the relay 28, and in position 13 a circuit will be established for the stepping magnet 13 of the magnetic 85 switch through the contact switch 25 in position 13. The energization of this magnet will set the brushes 1, 2 and 3 onto the second row of contacts 7, 8 and 9, which are connected with another connector switch, 90 which may then be tested.

In the modified form of invention shown in Figs. 2 and 3, the testing arrangement is adapted to test the operation of a series of switches such as are used in the arrangement 95 of a complete connection between a called and a calling line. Briefly stated, the testing arrangement when placed in operation, first seizes a line switch, which line switch then extends the connection to a first selector switch, from which point the connection is extended through such first selector switch and a connector switch under the control of the testing arrangement, to a set of terminals in the connector switch leading back 100 to the testing arrangement. If this test connection is established within a predetermined time, the operation of the switches involved is considered to be standard, whereas if the predetermined time is exceeded, a 105 condition considered to be unstandard, a record of it is automatically made.

This testing arrangement, which is shown in the lower portion of Fig. 3, is similar in many respects to the testing arrangement already described, and it is thought that its construction will be readily understood from the description of the operation in setting up a test connection. 115

The terminals of the automatic switch 120 associated with the testing arrangement are in this case connected with the incoming conductors of a line switch at a point between the subscriber's line and such line switch. The line switch, which is shown 125 at the left of the Fig. 2, is of well-known construction and is therefore only shown diagrammatically. The same may be said of the first selector switch shown at the right of Fig. 2 and the connector switch 130

shown at the upper part of Fig. 8. As soon as the testing arrangement is started in operation by the closing of the manual switch 100, it being assumed that the brushes 101, 102 and 103 of the automatic switch associated with the testing arrangement have been brought into contact with the set of terminals indicated at 104, 105 and 106, terminal 104 being connected by means of conductor 107 to one limb of the line indicated at 108, and the terminal 105 being connected by means of the conductor 109 to the other branch 110 of the line, and the third terminal 106 being connected by the conductor 111 to the plunger magnet 112 of the line switch. As soon as the manual switch 100 is closed, the sequence switch indicated at 113 being in position 1, a circuit is closed for connecting relay 114 from battery, lower arm of the manual switch 100, sequence switch contact 115 in position 1, back contact and outer armature of relay 116, relay 114, back contact and left-hand armature of relay 117, to ground. Relay 114 in attracting its armature, connects the brushes 101, 102 and 103 in operative relation with the testing arrangement, and also at its lower armature closes a circuit including the relay 116 to the multiple terminals of the various connector switches which are connected to the testing arrangement. As soon as relay 114 is operated, the relay 117 is connected to the brush 103, and to contact 106 and conductor 111 through the brush 118, and, providing the line switch under test is busy, to ground at the first selector switch with which such line switch is connected. Therefore, the relay 117 will be energized from battery through the lower arm of the manual switch 100, sequence switch contact 115 (position 1), relay 117, sequence switch contact 129, brush 103, conductor 111, brush 136, outer armature of relay 147, which is energized while the selector is in use, to ground. Relay 117 being thus energized, establishes a locking circuit for itself at left armature and front contact independent of the circuit previously traced through the line switch. Relay 117 when thus energized, closes at its right-hand armature and front contact, a circuit from battery through the power magnet 113 of the sequence switch, right armature and front contact of relay 117, interrupter 119, upper arm of the manual switch 100, to ground. The sequence switch will thereupon move under the control of the interrupter 119 into position 13, and in position 13, will close an energizing circuit for the stepping magnet 120 from battery to the lower arm of the manual switch 100, sequence switch contact 115 (position 13), stepping magnet 120, to ground. The automatic switch of the testing arrangement will thereupon be stepped forward and will as-

sociate the testing arrangement with another line switch.

If the line switch is idle, the relay 117 will not be energized, and the sequence switch will be moved directly into position 2 under the influence of the interrupter 119 through the contact spring 121, position 1. Associated with the testing arrangement is an impulse sending device, comprising three impulse wheels 122, 123 and 124. Each of these wheels are adapted to send out the same number and combination of impulses but at different speeds. For example, the impulse wheel 122 may be operated automatically to send a combination of impulses, such, for example, as 3, 5, 2 at the rate of ten impulses per second, while wheels 123 and 124 are adapted to send out the same combination of impulses at the rate of twelve impulses per second, and eight impulses per second, respectively. The contacts in the connector switches which are indicated at 125, 126 and 127, represent in all of the connector switches the number corresponding to the testing arrangement.

As soon as the sequence switch reaches position 2, the sequence switch contacts 128 and 130 being closed and the contact springs 131 operated by the first impulse wheel 122 being also closed, a circuit is established for the line relay 132 of the line switch, from battery, relay 132, outer left-hand armature and back contact of plunger magnet 112, line 108, conductor 107, contact 104, brush 101, armature and contact of relay 114, contact spring 128 in position 2, contact spring 133 also in position 2, interrupter springs 131, contact spring 130 in position 2, contact spring 129 in position 2, armature and contact of relay 114, brush 102, contact 105, conductor 109, branch at line 110, armature and back contact of plunger relay 112, to ground.

In response to the energization of line relay 132, a circuit is closed for the plunger magnet 112 which may be traced from battery, through the left armature and back contact of the lock relay 180, through the left-hand winding of the plunger magnet 112, armature and front contact of line relay 132 to ground. The plunger magnet thereupon operates and brings the brushes indicated at 134, 135, 136 and 137 into engagement with the contacts of a trunk leading to a first selector, such contacts being indicated at 138, 139, 140 and 141.

As the present invention is not concerned with the operation of the master switch, which is associated with a plurality of the line switches, the operation of such master switch will not be described in detail. The trip magnet 143, the solenoid 142, the lock relay 180, the starting relay 144, the supervisory relay 148, form a part of the master switch arrangement, and are diagrammati-

cally shown on the drawing. As soon as a line switch has seized an idle trunk leading to a selector switch, a circuit is established for the line relay 145 of such selector switch 5 from battery through the right-hand winding of said line relay, through the upper armature and back contact of relay 146, from thence over one end of the trunk line to terminal 138, brush 134, conductor 108, 10 conductor 107, terminal 104, brush 101, upper armature and contact of relay 114, contact spring 128 in position 2, contact spring 133 in position 2, normally closed spring 131, contact spring 130 in position 2, contact 15 spring 129 in position 2, brush 102, terminal 105, conductor 109, conductor 108, 20 brush 135, terminal 139, lower armature and back contact of relay 146, left-hand winding of line relay 145 to ground. Relay 145 operates and closes a circuit for the slow-release relay 147 from battery, through the winding of such slow-release relay, front contact and armature of relay 145 to ground. Relay 147 in attracting its armature establishes a 25 circuit for the vertical magnet 149 and slow-release relay 181 of the selector switch. As the impulse wheel 122 rotates, the circuit for the line relay just traced will be interrupted three times and the armature of the line 30 relay will close the circuit for the vertical magnet 149 three times from battery, through the vertical magnet 149, slow-release relay 181, front contact and inner armature of slow relay 147, lower armature 35 and contact of relay 146, back contact and armature of line relay 145 to ground. The slow-release relay 181 will be energized in this circuit in response to the first deenergization of the relay 145. Thereupon an energizing circuit for the private 40 magnet 150 will be established at the armature and front contact of relay 181, which will be maintained energized until the first 45 series of interruptions has ceased, when in response to the long energization of the relay 145, the relay 181 will be deenergized. However, as relay 150 closes at its armature and front contact, a locking circuit for itself 50 by way of conductor 161 and back contact of stepping magnet 152, through the vertical off-normal switch 153, to ground at the outer armature and contact of relay 147, it will remain energized. The relay 150, therefore, being energized, an energizing circuit is 55 established for the rotary stepping magnet 152 from battery, through such magnet, armature and back contact of such magnet, armature and back contact of relay 181, armature and front contact of relay 150, 60 conductor 151, right-hand armature and back contact of relay 152, vertical off-normal spring 153, outer armature and contact of relay 147 to ground. Relay 152, being energized, breaks its own circuit at its left-hand 65 armature and contact, and upon each for-

ward movement of its armature, steps the selector switch brushes 154, 155 and 156 one step in the rotary direction, hunting for an idle trunk. As long as the test brush 154 passes over contacts associated with trunks 70 leading to a busy connector, the relay 150 will be maintained energized through ground on the test conductors of the busy trunks, and the switch will continue to step. As soon, however, as an idle trunk is found, 75 the energizing circuit for the private magnet 150 will be interrupted at the right-hand armature of such magnet and the relay 150 will be deenergized, and will open the circuit of the rotary magnet 152, stopping the 80 switch.

Relay 150 being deenergized, a circuit is established for the relay 146 from battery, through such relay 146, back contact and armature of relay 150, conductor 151, back 85 contact and armature of relay 152, vertical off-normal switch 153, to ground at the outer left armature of the relay 147. The relay 146 in energizing, extends the connection to line relay 160 of the connector switch which 90 has been seized. The line relay 160 of the connector switch is therefore energized over a circuit from battery, through the upper winding of relay 160, upper armature and back contact of relay 161, to the terminal 95 157, and from thence by way of brushes of the selector switch and line switch to the normally closed contact springs 131 of the impulse wheel 122, and back also through the brushes of the line switch and selector switch 100 to the inner lower armature of relay 161 and back contact and lower winding of relay 160 to ground.

A first and second set of teeth on the interrupter wheel are spaced apart an amount 105 sufficient to maintain the contact springs 131 closed during the hunting operation of the selector switch. Upon the initial energization of the line relay 160, the slow-release relay 182 is energized and as the line relay 110 160 deenergizes in response to the first interruption, a circuit is closed from battery, through the side-switch arm 162, in position 1, through the vertical magnet 163, slow-release relay 164, armature and front contact 115 of slow-release relay 161, back contact and armature of the line relay 160 to ground. In response to the second series of interruptions, the vertical magnet 163 will be operated five times and will step the brushes 120 of the connector switch to the fifth level of terminals in such a switch. In response to the long energization of the line relay 160, following the second series of interruptions, the relay 164 will release, whereupon the 125 circuit for the energization of private relay 165 will be opened. The release of the private magnet 165 steps the side-switch into position 2. When, in response to the last series of impulses, line relay 160 is again 130

intermittently energized and deenergized, the relay 182 being thereby energized, a circuit is established to cause the intermittent energization and deenergization of the rotary magnet 183 from battery, through the side-switch arm 162 in position 2, rotary magnet 183, outer armature and back contact of relay 166, relay 164, right hand armature and front contact of relay 182, armature and back contact of relay 160 to ground.

In response to the intermittent energization and deenergization of the rotary magnet 183, the brushes 167, 168 and 169 of the connector switch are brought into contact with the contacts 125, 126 and 127 leading to the testing arrangement.

As the testing arrangement connected to these contacts will always be in condition to be connected to by such brushes, the contacts will test as an idle line and the side switch will be moved to position 3 in a well-known manner. In position 3 of the side switch, a circuit is established for the relay 172 of the testing arrangement from battery, through relay 172, terminal 127, brush 169, side-switch arm 170 in position 3, to ground. The operation of the relay 172 closes the ringing circuit which includes the relay 116. Also in position 3 of the side switch, a circuit is established for the ringing relay 171 from battery through the side-switch arm 162 in position 3, right armature and back contact of the ringing cut-off relay 184, relay 171, interrupter 173 to ground. The intermittent operation of the relay 171 in this circuit intermittently connects generator leads 174, 175, through the brushes 167, 168, and contacts 125, 126, to the circuit previously traced including the relay 116. The relay 116 is energized in response to this ringing current and opens at its outer left-hand armature and back contact a circuit previously traced for the relay 114, which in releasing its armature, opens the ringing circuit.

During the release of relay 114, the testing arrangement including the impulse wheel is disconnected from the brushes 101, 102, 103, and hence the line switch, first selector switch, and connector switch will all be restored to normal, as the relay 114 releasing, operates in identically the same manner as though the calling subscriber replaces his receiver. The relay 116 when energized, as described above, also closes at its inner armature and contact, a circuit from battery, through the power magnet 113 of the sequence switch contact 121 in position 2, inner armature and contact of relay 116 to ground, whereupon the sequence switch moves into position 3.

Relay 185, similar to relay 52 of Fig. 1, has an energizing circuit closed for itself in position 2 through the sequence switch contact 176, but since we will assume that

the connection set up through the line switch, the first selector and the connector has been established within the allowable time limit, it fails to operate before the movement of the sequence switch into position 3.

In response to the operation of the interrupter 119 acting through the contact spring 121 in position 3, the sequence switch moves to position 4. However, as soon as the relay 116 releases, the relay 114 is energized and the testing arrangement operates to test and seize on the line switch again, and under the influence of the impulse wheel 123, to establish the connection back to the testing arrangement over again. If this connection is established successfully within the predetermined time, relay 116 is again operated, the line switch selector and connector are restored to normal, and the sequence switch is stepped into position 5 and from thence into position 6.

In position 6 the same operation and test is repeated under the influence of the impulse wheel 124. It will be thus observed in the even positions of the sequence switch, the testing arrangement will seize and test a line switch by setting up a connection including such line switch, and if such connection is established within the predetermined allowable time, the relay 116 is operated to step the sequence switch into the next odd position.

This operation is again repeated in positions 8, 10 and 12, and the line switch is tested under the control of the impulse wheels 123 and 124 respectively. In these positions of the sequence switch, however, the capacity 186 and the resistance 186 are connected in the impulse circuit. When this last test is accomplished, and the relay 116 is operated in position 12, the sequence switch is driven into position 13 in the well-known manner. In this position the stepping magnet 120 is energized, and the brushes of the automatic switch indicated at 101, 102, and 103, are stepped into contact with the next set of terminals for the purpose of testing another line switch.

If the line switch, and incidentally the selector switch and connector switch used in connection therewith operate in the standard manner in response to all of the tests, six complete connections will be established, the line switch being tested at three different speeds of impulses under two different line conditions.

A recording magnet is shown at 185, which recording magnet is controlled by a sequence switch contact 176, closed in the even positions of the sequence switch, in which positions the testing takes place. This recording magnet as previously described is so adjusted that it will operate only after a predetermined time interval, so

that if the test connections are set up within the standard predetermined time, the circuit of the recorder magnet in each case will be opened in the odd position of the sequence switch before such time has expired. If on the other hand any single one of these six test connections is not established within the predetermined allowable time, the recorder magnet 185 will operate and record 10 an unstandard condition.

In addition, the recorder magnet will close at its left hand armature and contact a circuit for the wipe-out relay 117 from battery to the lower arm of the manual switch 100, 15 sequence switch contact 115, in position 1 to 12, relay 117, armature and front contact of the recorder magnet 185 to ground.

The operation of the relay 117 under these conditions causes exactly the same result as 20 the operation of such relay when the line switch under test was found to be busy. That is to say, the testing arrangement will be disconnected from the brushes of the automatic switch and such brushes will be 25 stepped into contact with another set of terminals.

What is claimed is:

1. A testing arrangement for testing the 30 operation of automatic selector switches comprising means for operating such switch to direct the movable contacts thereof to a predetermined set of stationary contacts, a recording device, a timing device, and means controlled through such contacts to prevent 35 the operation of recording device.

2. An arrangement for testing automatic 40 selector switches comprising a selector switch, means to send impulses to the operating mechanism thereof, contacts in such switch adapted to be selected by such switch in response to such controlling impulses, a recording device, and means controlled over such contacts for controlling such recording device.

45 3. A testing arrangement for testing the operation of automatic selector switches comprising automatic means for sending impulses to such switch to direct it to a particular set of contacts, recording means, and 50 means for controlling such recording means rendered operative when such switch makes connection with such particular set of contacts.

4. A testing arrangement for testing the 55 operation of automatic selector switches comprising a timing device and a recording device controlled thereby, means for starting the switch under test into operation and for simultaneously rendering said timing 60 device operative, and means controlled by the switch in completing its operation to remove the recorder from the control of such timing device, provided the switch completes its operation prior to the completion 65 of the operation of the timing device.

5. A testing arrangement for testing the 70 operation of automatic selector switches comprising automatic impulse - sending means, means for automatically associating such impulse-sending means with the switch to be tested, recording means, and means controlled by the operation of such selector switch in response to such impulses to control such recording means.

6. A testing arrangement for automatic 75 selector switches comprising means for producing a series of impulses, means for associating such impulse-producing means with a switch to be tested, a set of contacts in such switch to which the brushes of such switch are adapted to be directed in response to such impulses, recording means, and means controlled over such set of contacts for controlling such recording means.

7. A testing arrangement for testing automatic 85 selector switches comprising means to test a selector switch to determine if it is idle, means to seize such selector switch if idle, and prevent its seizure by other switches, means for establishing standard 90 operating conditions in such selector switch, a recording device, and means for controlling such recording device controlled by the operation of such selector switch in response to such standard operating conditions. 95

8. A testing arrangement for testing automatic selector switches comprising means for automatically operating a selector switch under different conditions, recording means, and means controlled by the operation of 100 such selector switch for controlling such recording means.

9. A testing arrangement for testing the 10. operation of automatic selecting switches comprising means for automatically operating a switch at different speeds, a timing device, and a recording device adapted to be controlled by such timing device, and means operated if the switch completes its operation within a predetermined time for removing such recording device from the control of such timing device. 110

10. A testing arrangement for automatic connector switches comprising means for establishing standard operating conditions 115 in a connector switch to connect such connector switch to a particular set of stationary terminals, a recording device, means associated with such connector switch to impress ringing current on such set of terminals, and means responsive to such ringing current for controlling the operation of the recording device. 120

11. A testing arrangement for testing the 125 operation of a plurality of automatic switches comprising means for establishing a test connection over such switches, a recording device, and means controlled by the establishment of such connection for controlling such recording device. 130

12. A testing arrangement for testing the operation of automatic telephone exchange systems comprising means for automatically establishing operating conditions normally established by the calling subscriber in initiating a call, a recording device, and means responsive to the standard operation of the system in establishing a connection for controlling such recording device.
- 10 13. A testing arrangement for testing the operation of an automatic telephone exchange system comprising means for automatically duplicating the operations normally performed by a calling subscriber in initiating a call, means for automatically duplicating the operations normally performed by a called subscriber in responding to the automatic establishment of the call
- thus initiated, a recording device, and means controlled by the establishment of the call 20 to control such recording device.
14. A testing arrangement for testing the operation of an automatic line switch comprising means for automatically establishing operating conditions in a line switch, 25 automatic means for successively associating such first mentioned means with a plurality of such switches, a recording device, and means controlled by such switch in its operation for controlling such recording device.

In witness whereof, I hereunto subscribe my name this 30th day of October A. D. 1916.

HENRY P. CLAUSEN.
